COMBINATION FUEL PUMP AND FUEL INJECTOR FOR DIESEL ENGINES

Filed Nov. 18, 1929

UNITED STATES PATENT OFFICE

HENRY LE PUL, OF HEMPSTEAD, NEW YORK

COMBINATION FUEL PUMP AND FUEL INJECTOR FOR DIESEL ENGINES

Application filed November 18, 1929. Serial No. 407,802.

This invention relates to new and useful improvements in fuel injectors for Diesel engines and has more particular reference to a novel combination pump and injector.

5 The invention has for an object the provision of a device of the class mentioned which is of simple durable construction, dependable in use and efficient in action, and which can be manufactured and sold at a reasonable cost.

The invention proposes a plunger for operation by the cam shaft of an engine and working in a body member formed with an inlet passage connecting with a fuel compression chamber, said plunger arranged upon its injecting stroke to pass said inlet passage and entrap and compress the fuel within the chamber, and a blow-off valve connected with said fuel chamber for directing the discharge of the fuel under pressure into a cylinder of said engine. The invention further proposes the provision of separate body sections constituting the said body and one of said body sections being provided 25 with said inlet passage and adjustable in position for determining the size of the fuel compression chamber for feeding regulated quantities of fuel to the engine for throttle control.

30 As is well known, it is necessary to inject solid fuel at high pressures into Diesel engines. The customary arrangement for doing this is the provision of the fuel pump external to and not a part of the engine for supplying fuel under the desired pressures, and the provision of an injector on each cylinder for controlling the injection of the fuel under pressure into the engine. The present invention is calculated to simultaneously raise the fuel to the proper pressure and to inject it into the engine. This arrangement permits common parts for raising the pressure and for injecting and thus produces a saving all around in addition to gaining efficiency due to a reduction of working parts.

35 For further comprehension of the invention, and of the objects and advantages thereof, reference will be had to the following description and accompanying drawings, and

to the appended claims in which the various novel features of the invention are more particularly set forth.

In the accompanying drawings forming a material part of this disclosure:—

Fig. 1 is a vertical sectional view of a combination pump and injector constructed according to this invention, certain parts being shown in elevation.

Fig. 2 is a horizontal sectional view taken 60 on the line 2—2 of Fig. 1.

Fig. 3 is a horizontal sectional view taken on the line 3—3 of Fig. 1, and

Fig. 4 is an enlarged detailed view of a portion of Fig. 1 showing all parts in section. 65

The combination fuel pump and fuel injector for Diesel engines consists of a plunger 10 for operation by the cam shaft of an engine and working in a body member 11 formed with an inlet passage 12 connecting 70 with a fuel compression chamber 13, said plunger 10 being arranged upon its injecting stroke to pass said inlet passage 12 and entrap and compress the fuel within the chamber 13, and a blow-off valve 14 connected with 75 fuel chamber 13 for directing the discharge of fuel under pressure into a cylinder of the said engine. The body 11 is made from several sections, only one of said sections being provided with the said inlet passage 12. 80 This section is adjustable in position for determining the size of the fuel compression chamber 13 for feeding regulated quantities of fuel to the engine for throttle control.

The said body member 11 consists of an 85 inner section 15, an intermediate section 16 and an outer section 17. The inner section 15 has a central bore 18 extending its complete length, and also has a bottom reduced portion 19, a central flange portion 20 and a 90 top externally threaded portion 21.

The said intermediate section 16 has a central bore 22 extending its full length and is slidably mounted on the bottom reduced portion 19 of the inner section 15. The intermediate section 16 extends materially below the bottom end of the inner section 15. A packing gland 23 is threadedly engaged in the intermediate section and packing 24 is clamped beneath the gland and between the 100

inner and intermediate sections for providing a fuel tight connection. The intermediate section 16 is formed with lateral rack teeth 25, and with a transverse aperture constituting the said inlet passage 12. This aperture is positioned a small distance below the bottom end of the inner section 15.

The said outer section 17 is provided with a central bore 26 extending thru its top end to a small distance from the bottom end, and is adapted for attachment upon the cylinder of an engine. The outer section terminates at the top in a pair of lugs 27 which are engaged against the bottom side of the said central flange 20. Screws 28 engage thru the flange and into the lugs for holding the outer section in fixed relation to the inner section. A lateral passage 29 in the outer section 17 aligns with the passage 12 in the central section. A pair of lugs 30 project from one side of the outer section 17 and support a pin 31 carrying a rocker arm 32 with teeth at one end meshing with the rack teeth 25. A control lever 33 is attached upon the pin 31 so that upon motion of the lever, the rocker arm moves for raising or lowering the intermediate body section 16. A valve seat 34 is formed in the outer body section 17 at the bottom of the bore 26 and connects with a passage 35 for discharging into a cylinder of the engine.

The said plunger 10 has a finished central portion 36 and an enlarged bottom head 37. The central portion 36 is slidably engaged thru the bore of the inner section 15 and is formed with a plurality of packing grooves 38 adapted to be filled with oil for forming an oil packing. A packing gland 39 threadedly engages in the inner section and forces packing material 40 tightly between the inner section and the central portion of the plunger rod for forming a liquid tight joint.

The enlarged head portion 37 of the plunger is disposed within the intermediate body section 16 and is a slidable fit in its central bore. The top of the enlarged head portion 37 is slightly spaced from the bottom end of the inner body section 15 providing a space 45 which constitutes the fuel chamber 13. A transverse fuel aperture 45 is formed within the plunger 10 and communicates with the fuel chamber 13. A longitudinal fuel passage 46 connects with the transverse passage 45 and communicates with a bottom bore 47 formed in the bottom end of the plunger 10. This bore is so arranged to provide a valve seat 48.

A bottom plug 49 threadedly engages on the bottom end of the enlarged head 37 of the plunger and is formed with a bottom projection 50 constituting a valve head for acting against the said valve seat 34 in the outer body section 17. Fuel passage grooves 51 extend from the valve head 50 to a bore 52

within the bottom plug 49 and which aligns with the bore 47 in the plunger. A valve head 53 is slidably engaged within the bores 47 and 52. An expansion spring 54 normally urges the valve head against the seat 48.

A filler rod 55 is attached upon the valve head and passes thru the central opening of the spring 54 so as to fill up all excess spaces for reducing the compass of fuel collecting in the bore 47 and 52. The valve head 53 is slightly shorter than the overall length of the bores 47 and 52 so as to provide a slight space 56 permitting a slight longitudinal movement of the valve. As shown in Fig. 4 the valve is of hollow construction so as to house the expansion spring 54. A spiral fuel passage groove 57 is formed upon the periphery of the valve 53 so as to permit the passage of fuel from the longitudinal passage 46 to the passages 51 and hence, if the valve 50 is open, to the passage 35.

A spring housing 58 is threadedly engaged upon the threaded portion 21 of the inner body section. A collar 59 is fixed upon the plunger 10 and an expansion spring 60 acts between the collar and the spring housing 58 for normally urging the plunger downwards. Lugs 61 project from the spring housing 58 and support a pin 62 carrying a rocker arm 63 engaging the bottom side of the collar 59. A lever 64 is fixed upon the pin 62 and is intended for connection with the cam shaft of the engine.

In operation of the device, a supply of fuel is fed into the passage 29. This fuel enters the fuel chamber 13 thru the passage 12. At the proper moment as determined by the cam shaft of the engine, the lever 64 is moved so that the rocker arm 63 lifts the plunger 10. As the plunger moves upwards, the head portion 37 forces back all excess fuel from the fuel chamber 13 until it passes the passage 12 and then compresses the entrapped fuel within the chamber 13. Continued upward motion of the plunger soon raises the pressure of the entrapped fuel to a predetermined amount as determined by the strength of the spring 54.

As this pressure is reached, the valve 53 automatically moves downwards and the fuel is then free to enter the passage 46, continue along the spiral groove 57, continue along the passages 51 and finally discharge from the passage 35 into the cylinder of the engine. Obviously, this fuel is discharged at a high pressure which is necessary since the pressure within the cylinder of a Diesel engine during intake is about 500 pounds. It is very easy to raise a pressure of the inlet fuel to 5,000 pounds or more with this arrangement.

As the plunger 10 moves upward a chamber will be formed under the bottom plug 49 of the plunger head 37. This chamber will increase at a greater rate than the decrease of the annular fuel chamber 13. As this cham-

ber is formed, hot air from within the cylinder of the engine will pass through the passage 35 to fill the same. Simultaneous with this passage, fuel which is pressed out from the annular chamber 13 will be discharged at a great velocity against the conical sides of the seat 34 and there be deflected through the passage 35. The valve 53 opens when the fuel oil is under a pressure of 5,000 lbs. which, due to the velocity, can easily take the right of way through the passage 35 against incoming air which at most is only at a pressure of 500 lbs. This incoming air will cause burning of the fuel within the newly formed compartment which will cause the pressure within the newly formed compartment to instantly build up and be at a greater pressure than the pressure within the cylinder. The fuel which is discharged when the valve 53 opens is in liquid form, but after it strikes the conical portion of the valve 34, will be immediately partially vaporized and it is for this reason that there will not be a large building up of liquid fuel within the newly formed chamber under the plunger head 37. When the plunger head moves back to its original position, all of the vapors and all of the liquid fuel within the newly formed chamber will be discharged into the cylinder of the engine. It is pointed out that the volume of air in the newly formed chamber is small and can support but a very small percentage of the combustible property of the fuel oil discharged on each stroke (for example, from 1% to 5%) so that a large percentage of combustion takes place in the cylinder of the Diesel engine.

The quantity of fuel injected into the engine at each operation of the device may be controlled by manipulation of the lever 33. Motion of the lever moves the rocker arm 32 and consequently raises or lowers the intermediate body section 16. As the body section is raised, the position of the fuel passage 12 is changed relative to the bottom end of the inner body section 15. Consequently the size of the portion of the fuel chamber which holds the entrapped fuel is varied.

While I have illustrated and described my invention with some degree of particularity, I realize that in practice various alterations therein may be made. I therefore reserve the right and privilege of changing the form of the details of construction or otherwise altering the arrangement of the correlated parts without departing from the spirit or the scope of the appended claims.

Having thus described my invention, what I claim as new, and desire to secure by United States Letters Patent is:—

1. In a combination fuel pump and fuel injector for Diesel engines, a body member comprising an inner section with a reduced lower end and a central bore, an intermediate section slidably mounted on said reduced end

and extending below said reduced end and formed with a fuel inlet passage terminating slightly below the reduced end and in a fuel compression chamber, and an outer section encasing said intermediate section and fixedly connected with the inner section and formed with a fuel passage aligning with said inlet passage, a plunger slidably mounted in the bore of the inner body section and formed with an enlarged head slidably mounted within the portion of the intermediate body section below the inner body section and normally slightly spaced from the lower end of the inner body section for forming said fuel compression chamber, a valve head on the plunger and engaging with its end against a valve seat on the outer body section communicating with a passage constituting a fuel outlet, a blow-off valve in said plunger interposed in a passage between said fuel compression chamber and the end of said valve head, and means for adjusting the position of the intermediate body section for adjustments of the size of a portion of said fuel compression chamber in which fuel is entrapped upon motion of said plunger to move its valve head from said valve seat.

2. In a combination fuel pump and fuel injector for Diesel engines, a body member comprising an inner section with a reduced lower end and a central bore, an intermediate section slidably mounted on said reduced end and extending below said reduced end and formed with a fuel inlet passage terminating slightly below the reduced end and in a fuel compression chamber, and an outer section encasing said intermediate section and fixedly connected with the inner section and formed with a fuel passage aligning with said inlet passage, a plunger slidably mounted in the bore of the inner body section and formed with an enlarged head slidably mounted within the portion of the intermediate body section below the inner body section and normally slightly spaced from the lower end of the inner body section for forming said fuel compression chamber, a valve head on the plunger and engaging with its end against a valve seat on the outer body section communicating with a passage constituting a fuel outlet, a blow-off valve in said plunger interposed in a passage between said fuel compression chamber and the end of said valve head, and means for adjusting the position of the intermediate body section for adjustments of the size of a portion of said fuel compression chamber in which fuel is entrapped upon motion of said plunger to move its valve head from said valve seat, comprising lateral rack teeth on said intermediate body section, a rock arm with teeth meshing with said rack teeth and pivotally supported on said outer body section, and means for moving the rocker arm.

3. In a combination fuel pump and fuel

injector for Diesel engines, a body member comprising an inner section with a reduced lower end and a central bore, an intermediate section engaged on said reduced end and extending below said reduced end and formed with a fuel inlet passage terminating slightly below the reduced end and in a fuel compression chamber and having lateral teeth at the top, and an outer section encasing said intermediate section and fixedly connected with the inner section and formed with a fuel passage aligning with said inlet passage, a plunger slidably mounted in the bore of the inner body section and formed with an enlarged head slidably mounted within the portion of the intermediate body section below the inner body section and normally slightly spaced from the lower end of the inner body section for forming said fuel compression chamber, a valve head on the plunger and engaging with its end against a valve seat on the outer body section communicating with a passage constituting a fuel outlet, a blow-off valve in said plunger interposed in a passage between said fuel compression chamber and the end of said valve head, a lug supported on one side of said outer section, a rocker arm pivotally mounted upon said lug and having teeth meshing with said teeth on the intermediate section, and a control lever connected with said rocker arm to move the intermediate section when desired.

Signed at New York, in the county of New York and State of New York, this 9th day
35 of November, A. D. 1929.
